UNITED STATES PATENT OFFICE.

PETER NIEWIAROWSKI, OF OMAHA, NEBRASKA.

ANGLE SCREW-DRIVER.

1,320,488.

Specification of Letters Patent.

Patented Nov. 4, 1919.

Application filed April 16, 1919. Serial No. 290,513.

To all whom it may concern:

Be it known that I, PETER NIEWIAROWSKI, a citizen of Russia-Poland, residing at Omaha, county of Douglas, and State of Nebraska, have invented certain new and useful Improvements in Angle Screw-Drivers, of which the following is a specification.

This invention relates to improvements 10 in tool holders, and particularly to types which may be used at an angle relative to their central axis.

The principal object of this invention is to provide a tool holding device carrying an 15 operative element, which may be actuated either in a plane coincident with the axis of the handle or at an angle thereto.

This object is attained by the novel construction and combination of parts herein- 20 after described, and shown in the accompanying drawings, forming a material part of this disclosure, and in which—

Figure 1 is a partial side elevational, and 25 partial sectional view taken through a tool holder made in accordance with the invention.

Fig. 2 is a fragmentary sectional view 30 showing the parts disposed in another position, and

Fig. 3 is an end view of the extension element.

In carrying out the invention, a body or head portion 10 formed with two extending elements, respectively 11 and 12, disposed 35 at a right angle, a chamber 14, being formed in the head element, at the axis of the angles, the chamber having a heavy plate covering 15 extending along the side of the body, and bent at an angle to provide a bottom 40 portion 16.

Formed through the angular element 11 is a bored opening 18, in which is fitted a stem 19, having an enlargement 20, resting 45 upon the top of the body element 11, the stem continuing into a shank 21, rigidly engaged in a handle 22, held by a transverse pin 23, the handle being of any preferred shape whatever.

Fixed upon the shank 19, is a bevel gear 50 25, its back resting against the wall of the chamber 14, the teeth meshing with another gear 26, fixed upon a stem 27 extending out-

ward through the opening 28, in the angular element 12, and terminating in an offset shouldered projection 29, which normally 55 extends outward to a slight distance beyond the outer end of the element 12.

Similarly, another offset extension 30 forms the terminal of the shank 19, which extends through an opening in the cover 60 plate 16, and which obviously may be rotated by operating the handle.

Formed in the outer surface of the angular element 12 are a pair of undercut openings 32, receptive of the headed pins 33, 65 similar openings 34, being formed through the lower cover plate 16, the pins 33 being set in the outer end of an oval or barrel shaped handle 35, having a cylindrical bore 36, receptive of the stem 29, and provided 70 with screw threads 37, by which is attached a hollow cap 38, containing a chamber 39, in which is operatively engaged a pair of spring jaws 40, the same being held by screws 41, within the chamber 42, formed 75 in the handle element 35.

A tool shank 44, is formed with an offset shoulder at its upper end 45, engageable with the shanks 29 or 30, and is formed with an annular recess 46, receptive of the detent 80 elements 40', whereby the shank 44 is held in engagement, the shank terminating in an operating implement, as the screw driver 48 indicated.

From the foregoing it will be seen that 85 a convenient and effective implement has been disclosed, which may be used in the ordinary manner as a plain screw driver or which, by disengaging the handle body 35 from the end of the main body 10 and applying the same to the lateral extension 12, a screw may be driven in a plane at right angles to the axis of the handle in an effective manner.

Having thus described my invention, 95 what I claim as new, and desire to secure by Letters Patent, is—

A convertible straight line or angular tool driver, comprising the combination with a chambered body having two portions 100 perforated at an angle to each other and providing bearings and an aperture opposite one of said bearings, shafts journaled in said bearings each of them having an

exposed end shaped to engage and rotate a bit or tool and one of them extending back through the aperture and the opposed bearing and having a handle on its other end,
5 gearing, connecting the two shafts, means for securing or holding a tool or bit with its end in engagement with one of the shaft

ends above mentioned, and means for interchangeably engaging said means with the body, in line with either of said bit engaging shaft ends. 10

In testimony whereof I have affixed my signature.

PETER NIEWIAROWSKI.
